NEEDLE THREADER

William S. Thompson, Monroe, Ohio

Application July 20, 1939, Serial No. 285,600

1 Claim. (Cl. 223—99)

The invention relates to a threading device and more particularly to a needle threader.

The primary object of the invention is a device of this character wherein a needle of any size can be automatically threaded through the eye end thereof and thereby eliminating the necessity of the hand threading of such needle which is rather tedious and vexing, especially when the needle eye is of extremely small size.

Another object of the invention is the provision of a device of this character wherein the different sizes of needles can be placed therein so that a thread may be introduced into the eye end of the selected needle for threading and the threading being had with dispatch.

A further object of the invention is the provision of a device of this character which is simple in its construction, thoroughly reliable and efficient in operation, being of a size so that it can be conveniently carried in a sewing bag, basket or on the person, possessed of but few parts, strong, durable, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention and pointed out in the claim hereunto appended.

In the accompanying drawing:

Figure 1 is a side elevation of the device constructed in accordance with the invention showing fragmentarily a needle held therein.

Figure 2 is a plan view.

Figure 3 is an enlarged fragmentary side elevation partly in section.

Figure 4 is a sectional view taken on the line 4—4 of Figure 3 looking in the direction of the arrows.

Figure 5 is a view similar to Figure 4 showing a needle threaded in the use of the device.

Figure 6 is a sectional view taken on the line 6—6 of Figure 1 looking in the direction of the arrows.

Figure 7 is an enlarged vertical transverse sectional view through the device.

Referring to the drawing in detail, A designates generally the device constructed in accordance with the invention and comprises a straight shank 10 for a major extent thereof being of uniform cross sectional size having at one end a curled finger engaging terminal 11 while at the opposite end is a head 12, this head 12 be-

ing cut into to provide a recess 13 opening in the direction of the shank 10 and effects an overhanging extension 14 with relation to the said shank 10, being parallel therewith and separated therefrom by the space 13. Provided in this extension are sockets 15, these being at right angles to the plane of the shank 10 and opening beyond the outermost and innermost sides of said extension. The sockets 15 are of different sizes to each other for selectively accommodating a needle, a portion thereof being indicated at 16. The purpose of having the sockets 15 of different sizes is to accommodate needles of different sizes with respect to each other. The needle at the eye end 17 thereof is counter-seated in a notch 18 formed in the shank 10 in confronting relation to its companion socket 15 so that the eye on the counter-seating thereof will have the opening therein in the longitudinal direction of the shank 10 which is elongated for a purpose presently described. Movable fitted upon the shank 10 is a sleeve-like runner or slide 19 from which projects at the end next to the recess 13 in the head 12 a threading hook 20 which is adapted to freely pass through the eye 17 in the needle 16 when it is desired to catch a thread 21 for the passing of this thread through the eye 17 for the threading of said needle.

In threading the needle 16 in the use of the device A the loose or free thread is placed transversely of the head 12 through the recess 13 on the side of the needle eye 17 remote from the slide 19 and its hook 20 so that when manipulating the slide 19 on the shank 10 this hook will first enter the eye 17 to engage with the thread 21 whereby on pulling upon this slide 19 in the direction of the terminal 11 the thread 21 engaged with the hook 20 will be drawn through the eye 17 of the needle 16 and thereby threading the latter whence the thread 21 engaged in the eye 17 of the needle will be disengaged from the hook 20 on the slide 19 and the needle threaded can be withdrawn from the head 12 of the device, the threading operation of the device being shown in Figures 3, 4 and 5 of the drawing.

What is claimed is:

A device of the character described comprising a straight flat-faced shank, a hook-like head formed at one end of the shank and having a bill in spaced parallel relation to the shank for overhanging it for a distance thereof with the space therebetween opening through opposite sides of said head, a sleeve-like runner slidably embracing the said shank and movable into the space 55

between the bill of the head and the said shank, the bill being provided with an opening accommodating a sewing needle for introducing its eye into the space between the bill and said shank, 5 the shank being provided with a seat for the eye of the needle and of a shape to hold the eye in confronting relation to the said runner, a thread-engaging extension on the runner of a size for penetrating the said eye and engagement of a 10 thread therewith when the runner is moved in

one direction and the pulling of the thread through the eye of the needle when the runner moves in an opposite direction, the said needle eye and the extension of the runner being visible at either side of the head when the eye and extension are within the space between the bill and the shank, and a finger-engaging terminal turned from the shank at the end thereof remote from the head. 5
